UNITED STATES PATENT OFFICE.

CHARLES N. WADE, OF PATERSON, NEW JERSEY.

TICKET PRINTING AND DELIVERY MACHINE.

Application filed January 19, 1920. Serial No. 352,322.

To all whom it may concern:

Be it known that I, CHARLES N. WADE, a citizen of the United States, residing at Paterson, in the county of Passaic and State 5 of New Jersey, have invented certain new and useful Improvements in Ticket Printing and Delivery Machines, of which the following is a specification.

This invention relates to a ticket printing 10 and delivery machine designed primarily to print and deliver, in rapid succession, different tickets of such type as are used by public service organizations.

I am aware that there have been devised 15 numerous ticket delivery and printing machines operating more or less successfully to deliver tickets in rapid succession, which tickets may have, at the option of the operator of the machine, different printed matter 20 on each ticket; such a machine is disclosed in Letters Patent, No. 1,359,938, granted to me November 23, 1920, the present application being a continuation in part of the application which eventuated in said 25 Letters Patent.

In the present invention, I provide a ticket printing and delivery machine of compact form which will print and deliver, in rapid succession, tickets of the street car transfer 30 or zone transfer type having printed thereon the name of the public utility issuing the transfer, the issuing line and the transfer line, the date, the number of the transfer, time of issue, and the time interval for 35 which the transfer is acceptable.

The invention also has for an object to store a continuous strip of paper which is fed through the ticket printing and delivery machine and is printed upon and is automatically severed into ticket lengths after 40 printing; and the ticket is finally delivered to the party desiring the transfer, all by a single operation of a single lever.

A further object of the invention is to provide mechanism whereby the printing elements may be varied manually for the initial setting of the machine and some of the printing elements thereafter varied automatically according to time or varied according to 45 each issue of a transfer in order to bring into play the proper printing faces.

The invention has as a further object the provision of a ticket printing machine of which the mechanism may be set before 50 turning it over to the operator of a vehicle such as a street car, for instance, and there-

after the only changes which will be necessary will be changes from the exterior of the machine so that the interior mechanism is not subjected to being tampered with by 60 the operator of the machine.

In the drawings:

Figure 1 is a perspective view of the ticket printing and delivery machine;

Fig. 2 is a side elevation of the mechanism of the machine intact but with the casing removed; 65

Fig. 3 is a side elevation of the mechanism viewed from the side opposite that shown in Fig. 2;

Fig. 4 is a bottom plan view of the mechanism;

Fig. 5 is a central longitudinal section;

Fig. 6 is a horizontal section on the line 6—6 of Fig. 2;

Fig. 7 is a transverse section on the line 7—7 of Fig. 3;

Fig. 8 is a transverse section on the line 8—8 of Fig. 2;

Fig. 9 is a perspective detail of the time 80 clock setting mechanism;

Fig. 10 is a diagrammatic view in plan of the arrangement of the printing faces when set to produce a transfer;

Fig. 11 is a fragmentary view showing a 85 modified form of paper strip feeding mechanism;

Fig. 12 is a top plan view of the complete machine;

Fig. 13 is a fragmentary view showing the 90 connections necessary for the modified form of paper strip feed.

The mechanism of the transfer printing and delivery machine, considering the same with the casing removed as shown in Figs. 95 2 and 3, consists of a frame 1 comprising two side members 2 and 3 each having suitable feet 4, 5 and 6 for fastening the mechanism in the casing as will later be described and such frame members are connected across by suitable upper structure carrying different units of the mechanism to be later set forth.

The mechanism consists of several different units interconnected for simultaneous cooperative action on the movement of a single lever and the detail description of the machine will be set forth in several parts each of which will relate to a separate unit of the mechanism. 105

Paper feed mechanism.—At the top of the frame 1 and near the rear of the machine 110

- are the parallel uprights 7 and 7' in the upper ends of which is journaled a paper storage roll carrying shaft 8 which extends transversely of the machine and is enlarged at one extremity to prevent it from slipping through the uprights; a spring cap member 9 pivoted at 10 encloses the enlarged end of the shaft 8 and retains the said shaft in place until such time as it is desired to replace the paper storage roll with a new roll. On the inside of the uprights 7 and 7' are spring tensioning fingers 11 and 11', the tines of which bear against the sides of the roll of paper 12 thereby tensioning the paper as it feeds through the machine. The paper strip 12 passes over a guide roll 13 having flanges 14 and journaled in the extensions 16 of the frame 1 by means of the shaft 15. Forwardly of the guide roll 13 and carried in extensions 17 supporting a shaft 18 is a paper feed roll 19 having a friction surfacing material 20 over which the paper strip passes; above the paper feed roll 19 is a pressure roll 21 mounted on a shaft 22 and the paper strip passes between the rolls 19 and 21 as clearly shown in Fig. 5. The shaft 18 is provided with a knob 23 at one end thereof for manually feeding the paper strip through the machine. This knob 23 is knurled on the periphery and provided with a plurality of facial radial divisions cooperating with a pointer 24 mounted by screws 25 on the frame 1 of the machine. The paper strip after passing between the rollers 19 and 21 continues horizontally through the machine and, at the forward end of the machine, the strip passes beneath a fixed knife 26 cooperating with a movable knife 27, mounted in vertical ways on the frame members 2 and 3, whereby to cut the strip into ticket lengths by mechanism hereinafter described in particular. The delivery plate 28 receives the cut ticket which is guided in channels 29 so that immediately on being severed the ticket will be delivered at the front of the machine.
- Ink ribbon mechanism*.—Following the course of the ticket strip and carried on rollers 30 and 31 at the front and rear of the machine, respectively, is the ink ribbon 32. The roller 30 is provided with flanges 33 and has its spindles 34 journaled in slots 35 in the side plates 36 secured to the frame 1 by screws 37. Ribbon tensioning means consisting of spring fingers 38 retain the roll 30 in place. The roll 31 is mounted in slots 39 of the extensions 16 and is retained in place by ribbon tensioning means comprising spring fingers 41 secured by screws 42 and riding on flanges 40 of the roller. The ribbon feed consists of a ratchet wheel 43 keyed to the end of the roller 30 and engaged by a pawl 44 pivoted at 45 to an arm 46 bifurcated as shown at 48 to slide over the end of the roller 30 between the plate
- 36 and the ratchet wheel 43, said pawl 44 being held in engagement with the ratchet wheel 43 by a spring 47 and therefore, as the arm 46 is raised and lowered, the ribbon which is secured at each end to the rolls 30 and 31 will be fed, due to said ratchet mechanism, from the roller 31 to the roller 30. Parallel with the rollers 30 and 31 are the members 30' and 31' under which the ribbon is trained and which serve to guide the ribbon in its course through the machine. The spindles of the rollers 30 and 31 are provided each with a milled head 340 to facilitate the tensioning of a new ribbon and rewinding of a ribbon upon the roller 31.
- Platen mechanism*.—A flat plate 50 constituting a platen is cut out on its four corners as shown at 51 in the bottom plan view, Fig. 4, and is arranged to be bodily displaced upwardly for printing, the members 52 integral with the frame 1 constituting guides therefor during its vertical movement. The platen is arranged beneath the paper ticket strip so that the said ticket strip passes between the ink ribbon and the platen. Beneath the platen and journaled in the frame 1 are two parallel platen cam shafts 53 and 54 carrying the pairs of cams 53' and 54' respectively which, as the shafts 53 and 54 are rotated in opposite directions engage the platen to cause the latter to rise and fall.
- Ticket strip severing mechanism*.—On the members 2 and 3 of the frame 1 beneath the platen 50 and journaled in boxes 55 secured in place by screws 56 is mounted a transverse member 57 having the longitudinally extending arms 58 and 58', the arm 58 being provided with a stud 59 having a head 60 and screwed through the arm 58. The stud 59 is adapted to be engaged by a cam-like protuberance 61 on a collar 62 keyed to the platen cam shaft 54 so that when the cam shaft 54 is rotated the cam-like protuberance 61 will engage the said stud 59 and by thus depressing the arm 58 will coincidentally raise the arm 58'. The arm 58' has mounted thereon the vertical knife 27 secured in place by the plate 64 held by screws 65, and the knife 27 is further braced by the spring member 66 bearing against the rear face of said knife 27 and insuring the proper shearing coaction between the knives 26 and 27. By this construction, the depression of the arm 58 will raise the knife 27 so that it will engage with the fixed knife 26 and shear the paper ticket strip between the knives. Intermediate the ends of the arm 58' is a stud 67 having a head 68 by which it may be screwed through the said arm, to cooperate with a cam 69 of a member 70 keyed to the platen cam shaft 53 so that, after actuation by the cam-like protuberance 61 of the cam

shaft 54 the member 70 will return the member 57 to its normal position.

Operating means.— Mounted on the studs 72 and 73 in the side member 3 of the frame 5 1 are pinions 74 and 75 meshing with pinions 76 and 77, respectively, on the platen cam shafts 53 and 54. One end of the cam shaft 53 is squared as at 78 to receive a crank 79 so that by turning the crank 79 10 the platen 50 is raised and lowered by means of the cams carried by the platen cam shafts 53 and 54 and likewise the knife 27 is actuated. An interrupted gear 80 on the platen cam shaft 54 meshes with a pinion 81, 15 at the proper time, on the paper feed roll shaft 18 and feeds the exact ticket length of the ticket strip over the platen 50 previous to the raising of the platen. The platen 50 is assisted in its return to the lowered position 20 by the leaf springs 82 secured in place on the side members 2 and 3 of the frame 1 by screws 83.

Station to station and direction printing means.— Above the platen 50 and the ribbon 25 and mounted in suitable cut-outs in the superstructure of the frame 1 are journaled the spindles of the longitudinally arranged parallel printing rollers 84, 85 and 86, 87. The rollers 84, 85 are provided each with 30 several printing faces extending longitudinally of the rollers and these printing faces bear the names of stations, while the rollers 86, 87 each have several printing faces bearing direction names such as North, 35 South, East and West. Fixed on the frame 1 in the space between the rollers of each pair, is a printing face bearing the word "to" so that the station printing means may print, as an example, "Governor to 40 Newark," and at the same time the direction indicating means may also print, for example, "north to east." The spindles of the rollers 84, 85 carry bevel pinions 84', 85' while the spindles of the 45 rolls 86, 87 carry bevel pinions 86', 87'. Similar bevel pinions 88 and 89 are mounted on vertical shafts 90 and 91 carried in the frame 1 and integral with these last named pinions are the gears 88', 89' which mesh 50 with similar gears 92, 93 carried on spindles which extend vertically up through the frame 1 and have keyed thereto the collars 96 each of which collars receives a spindle 97 extending through the casing of the machine 55 as shown in Fig. 1 and provided at the top with the disk-like members 97' having knobs 98 by which they may be turned to any desired position, pointers being provided on the exterior of the casing to indicate 60 on the members 97' which printing face of the respective printing rolls is in position to print. The direction indicating rollers 86 and 87 are similarly geared up to disk-like members 99 having knobs 100 and 65 may be similarly set according to the de-

sire of the operator of the machine and since the gearing mechanism of the rolls 86 and 87 is identical with that of the rolls 84, 85 such gearing will be given identical reference characters.

Transfer numbering mechanism.— This mechanism consists of a numbering machine of the impression type located in a suitable recess 101 in the upper structure of the frame 1 and is of such construction that the printing engagement of the platen 50 with one of the several printing faces of the numbering machine will cause the actuation of such machine each time the platen engages in printing relation therewith. It is not necessary to give a specific description of this numbering machine since any one of the numerous devices operating in this manner and now manufactured and forming a commercial article may be incorporated in the machine. The numbering machine is held in place by a suitable backing plate, not shown but placed over the opening of the recess 101 and which tightly presses the said numbering machine margin against the flange 102 which 70 forms a seat for the numbering machine; and said backing plate is secured in place by screws entering the holes 103. Adjacent the numbering machine recess is another cut-out 104 which accommodates, in the bearing 105 carried by the frame 1, a plurality of concentric telescopically mounted rotating dating shafts carrying finger knobs 106, 107, 108 and 109 crossed by an indicating pointer 110 mounted on the frame 1 by 75 suitable screw means. The other end of these telescopic shafts carries suitable printing disks 106', 107', 108' and 109' provided with printing faces, and of which the knob 106 carries the days of the week and printing disk 106' connected therewith carries printing faces corresponding to the days of the week; knob 107 carries peripheral designations corresponding to the months of the year while printing disk 107' carries printing faces corresponding to the months of the year; knob 108 carries peripheral indicia corresponding to the numerical days of the month and printing disk 108' connected therewith carries printing faces corresponding to the numerical designations of the days of the month; and knob 109 is divided into years while the printing face of disk 109' is correspondingly provided with printing means. These printing disks 80 are held in any set position by spring fingers 111 which engage the peripheries of the disks and hold the said disks in printing alignment after being set. These spring fingers are secured in place by screws 112. 85 Thus, from the foregoing, it will be seen that the proper setting of the printing disks will occasion, on actuation of the platen, the printing on a transfer of the day of the week, the month of the year, the day of 90 95 100 105 110 115 120 125 130

the month and the year in alignment immediately adjacent but at right angles to the number of the transfer. The frame 1, in the printing area also carries a fixed printing member which prints on the face of the transfer the time limit for which the transfer is good as, for instance, "Expires in fifteen minutes," as at 113, Fig. 10 and also at one end of the printing area of the machine is carried a printing plate bearing the name of the issuing company, as indicated at 114, Fig. 10. Forwardly of the central portion of the machine are two uprights 115 which carry the time printing mechanism which comprises, in detail a backing plate 117 and a front plate 118 between which is mounted a shaft 119 carrying a spring drum 120 containing the coil spring 121 and having the peripheral gear teeth 122. The spring within the drum may be wound by means of a winding spindle 123 carrying a gear 124 which meshes with a gear 125 on the end of the shaft 119, said spindle 123 being supported in the bracket 126, secured in place by screws 127 on the face of the front plate 118, the spindle being further supported by a bracket 128 so that the key engaging end 129 thereof may project through a suitable hole in the casing of the machine. The usual holding ratchet 122' is provided to insure proper application of the force of the spring. The motion of the drum 120 due to the inertia of the spring 121 is communicated to a spindle 130 by a pinion 131 carried on said spindle and meshing with the teeth 122 of the drum and the other end of said spindle 130 carries a large gear 132 which, in turn, meshes with a gear 133 on an escapement spindle 134 carrying the escapement wheel 135 with the pawl 137 pivoted at 138 and pressed into engagement with the ratchet wheel 136 by a spring 139 so that movement of the escapement wheel in one direction is imparted to the spindle. The shaft or spindle 134 has keyed thereto a cam 140, shaped as shown in Fig. 7, which is arranged to actuate a second escapement through the medium of the cam escapement arm 141 bearing on said cam as the latter rotates in the direction of the arrow indicated in Fig. 7. This arm 141 is drawn in toward the cam by a spring 142 connected with the arm at 143 and with the front plate 118 as indicated at 144. The arm is carried loosely upon a shaft 145 upon which is secured the escapement wheel 146 engaged by the pawls 147, 148, and 149. The pawl 149 also bears upon the periphery of the shaft engaging portion of the arm 141 and is adapted to enter the notch 150 therein, a spring 151 being provided to hold the pawl toward the arm 141 and the escapement wheel 146. As the arm 141 moves toward the high point of the cam 140, the lower wall of the notch 150 rides under the pawl

149 and releases the same from the escapement wheel. The pawl 152 pivoted on the shaft engaging portion of the arm 141 and actuated by a detent lever 153, mounted at 154 on said arm 141, engages the pawl 148 to lift the same out of the notches of the escapement wheel 146 just before the arm 141 leaves the point 155 of the cam 140 so that the escapement wheel 146 is allowed to move the distance requisite to shift elements of the time printing mechanism. The arm 141, of course, is provided with a pawl 141' to engage and actuate the escapement wheel. A member 152' is provided for disengaging the pawls 148 and 149 to permit free movement of escapement wheel 146.

The escapements hereinbefore mentioned control three printing disks 156, 157 and 158, respectively, mounted on the shaft 134 between the two plates 117 and 118. The escapement wheel 135 controls the printing disk or wheel 157 which carries printing faces corresponding to minutes of time and has sixty faces, while the escapement wheel 146 through the medium of two sets of gears 159 and 160 locked to the printing disks or wheels 156 and 158 controls the movement of these last named wheels. The wheel or disk 156 carries hourly designations covering the twenty-four hours of the day while the printing disk or wheel 158 carries A. M. and P. M. designations aligning with the hourly designations of the wheel 156, and the escapement wheel 146 is therefore only actuated by the cam 140 on every sixty minute period or lapse of time as indicated by a complete revolution of the escapement wheel 135 which is controlled in a manner to be hereinafter described. This mechanism, as will be seen, constitutes time printing means which may be automatically governed by clock mechanism.

Time clock mechanism.—The time clock mechanism consists of the usual clock mechanism having the plates 161, 162 separated by spacing means 163, and having the usual main spring barrel 164 of a clock mechanism, the spring of which is wound through the medium of a spindle 165 adapted to be engaged at 166 by a suitable key, this end of the said spindle projecting through the front end of the casing. The hour and minute hands 167, 168, respectively, are driven from the barrel 164 through suitable gearing 169 to indicate, at the front of the machine, the time which is to be printed on the transfer and such hands are geared back by pinions 170 and a shaft 171 secured at 172 to the member 173 carried by the cam 140 so that any setting of the hands of the clock will also set the time printing mechanism, such printing mechanism being assembled with the clock mechanism in such manner, to be hereinafter described, that the two correspond so that the time printed will

be registered also on the face of the clock. The clock hands and their attendant mechanism, which are of the usual type, are driven by the usual gear train through the medium of a pinion 174, driven by the main spring barrel 164, which in turn meshes with the other gearing to drive the hands of the clock. Such movement of the main spring barrel is communicated to a setting shaft 176, mounted in the frame plates 161 and 162 near the upper ends thereof, by a pinion 177 slidable with said shaft for engagement with the gear 175 carried by the main spring barrel, such pinion 177 being moved by the forked member 178 carried on a support 179 and moved through the medium of the lever 180 so that the pinion 177 and the gear 175 may be disengaged for setting of the hands of the clock and the time printing mechanism. When the shaft 176 is shifted forwardly to disengage the pinion 177 from the gear 175, a pinion 181 on the front end of said shaft is caused to engage the pinion 182 on the lower end of a spindle 183 which is provided with a knob 184 above the casing, said spindle 183 being mounted in a bracket 185 at the front of the clock frame and in the top of the casing and being held against dropping by the engagement of the knob with the casing. When the knob is rotated, the clock and the printing mechanism are set. The setting 176 carries a crank disk 186 at its rear end which is provided with a crank pin 187 engaging in the upper end of a slot 188 in an escapement lever 189, which is pivoted upon the frame plate 118 as at 190 and carries escapement end or tooth 191 engaging the escapement wheel 135 and has a pin 192 engaging in the slotted end 193 of another escapement member 194 pivoted at 195 so that rotative movement of the setting shaft 176 is translated into rocking movement of the two escapement levers, thus permitting minute interval movements of the escapement wheel 135 which, in turn, are transmitted to the minute printing disk 157. In this manner the movements of the hands of the clock are registered on the time printing mechanism. The clock mechanism is supported by uprights 196 secured to the side of the machine frame and which carry the brackets 197 and 128 for supporting the winding shafts 165 and 129 respectively. At the front of the machine is a platform 198 carrying a counting mechanism 199 which is adapted to register the total number of transfers issued by the machine and may be manually set by the knob 200 but is normally automatically actuated through the medium of the counter actuating shaft 201, having secured thereto an arm 202 which is actuated to the downward position by a spring 203 and has its lower end pivoted at 204 to a link 205; the lower end of said

link 205 being pivoted at 206 to the forward end of a lever 207 pivotally mounted on the frame 1 at 208 and having its tail arm 209 engaged by a cam 210 mounted on the crank end 78 of the platen cam shaft 53, so that each revolution of the crank 79 and its cam shaft 53 serves to raise the forward end of the lever 207 thereby elevating the link 205 and actuating the lever 202 to advance the counter mechanism 199 one number. The arm 46 of the ink ribbon mechanism is also pivoted at 210' to the same lever 207 and consequently the cam 210 also serves to elevate the arm 46 and actuate or advance the ribbon, thus providing for the ribbon feed and at the same time providing for registering or tallying the total number of transfers issued by the machine. If desired, the visible counting mechanism 199 may be set to register coincidently with the number printing mechanism of the transfer printing means so that the conductor will at all times be cognizant of the number of transfers issued and the number of the issuing transfer.

Exterior casing.—The mechanism is enclosed in a case 212 which is provided at the front with a sight opening 213 receiving the face of the clock so as to make the same visible and also is provided with sight openings 214 and 215 for the counter mechanism and clock setting mechanism respectively. The lever 180 of the clock setting mechanism has its knob end projecting through an opening 216 in the casing. Likewise the side of the casing is suitably formed at 217 to permit the actuation of the dating printing means from the outside of the casing. The side 218 of the casing is removable in any suitable manner. A latch 219 is fixed to the case at 220 to provide for holding the handle 79 in the upright position and locking means 221 is provided on the inside of the casing side 218 to prevent the handle 79 from coming off until released by raising said locking member 221. The face of the casing is open at 222 to permit the expulsion of the transfer. The top of the casing as before explained accommodates the four dials 97 and 99 with their respective pointers so that the operator of the machine may know how the machine is set and where to set it.

The operation of the machine is as follows:—The paper roll is suitably mounted as previously described and the strip threaded through the machine. The dating mechanism is set at the beginning of the day as is also the clock mechanism. The operator of the machine issuing transfers then turns the dials 97' and 99 to the points of transfer and the direction, respectively, and, after disengaging the member 219, rotates the crank 79 one full revolution which, through the medium of the cam shafts 53 and 54 connected for unison operation actu-

ates the respective mechanisms connected therewith such as the inking ribbon and counting mechanism, and, at the same time, raises the platen 50 to engage the same with 5 the paper strip, impressing the paper strip against the ribbon and the printing faces to print upon the surface of the paper strip the data to be recorded by the printing mechanism after which the continued movement 10 of the handle 79 lowers the platen and advances the strip through the machine a distance equal to the length of the ticket, the printed ticket issuing through the delivery opening 222. Just before the handle 15 again reaches its vertical position, the printed ticket is severed from the strip and the machine is ready for successive repeat operations to produce any number of transfers.

In reference to the modified form of paper strip feed as shown in Figures 11 and 13, the interrupted gear 81 meshes with a pinion 300 mounted on a stud 301 and connected by means of a crank pin 302 and connecting rod 303 with a crank pin 304 on a disk 305 carried 20 by a paper roll 306 forwardly of the machine and immediately at the rear of the delivery plate 28 and back of the knife 27, a compression roller 307 being mounted above the roll 306 to impart the necessary 25 pressure for moving the paper strip B. The construction of the machine embodying this modified form of paper feeding mechanism is identical with that described in connection with the preceding figures with the exception 30 that the paper is drawn through the machine as contradistinguished from pushing it through.

I claim:

1. The combination of a casing, a fixed 0 printing member within the casing, a pair of parallel printing rollers arranged above and cooperating with the fixed printing member, the axes of said rollers extending longitudinally of the fixed printing member, 45 means for adjusting the printing rollers from the exterior of the casing, a platen movable toward and from the printing members, means for feeding a paper strip longitudinally over the platen between the same and the printing members, and an inking ribbon 50 extending longitudinally over the platen between the paper strip and the printing members.

2. The combination of a casing, a fixed 55 printing member mounted in the casing, a pair of parallel station printing rollers arranged above and cooperating with the fixed printing member, the axes of the rollers extending longitudinally of the fixed printing member, a pair of parallel direction-printing rollers in axial alignment with the station-printing rollers, means for adjusting all said rollers from the exterior of the casing, a plurality of dating rollers arranged 60 adjacent the fixed printing member and hav-

ing concentric axes arranged transversely of said fixed printing member, means for adjusting the dating rollers from the exterior of the casing, a platen disposed below the fixed printing member and all said rollers 70 and movable toward and from the same, an inking ribbon extending longitudinally over the platen between the same and the fixed printing member and the rollers, and means for feeding a paper strip over the platen 75 between the same and the inking ribbon.

3. The combination of a casing, a frame within the casing, a fixed printing member supported in the frame, pairs of parallel printing rollers mounted above and co-operating with the fixed printing member pinions mounted in the frame adjacent the ends of the respective rollers and geared thereto, collars secured to the pinions, spindles secured in said collars and extending through the casing, indicator dials carried by said spindles exterior to the casing, and pointers on the casing cooperating with said dials.

4. The combination of a frame, printing 90 members mounted therein, a platen mounted in the frame below the printing members, springs secured in the frame and bearing on the platen to hold the same normally lowered, cams bearing against the under 95 side of the platen, and means for simultaneously rotating said cams whereby to effect raising and lowering of the platen.

5. The combination of a frame, printing members mounted therein, a platen arranged below the printing members, a fixed knife on the frame adjacent one end of the platen, an inking ribbon disposed between the platen and the printing members, means for feeding a paper strip over the platen 105 between the same and the inking ribbon and past the fixed knife, a movable knife mounted below the fixed knife to cooperate therewith, means to move the platen toward and from the printing members, and means whereby when the platen recedes the movable knife will be advanced to the fixed knife and sever the paper strip.

6. The combination of printing members, a platen, means for feeding a paper strip 115 over the platen between the same and the printing members, a fixed knife on the frame adjacent the discharge end of the platen, a train of gears below the platen including cam shafts, cams on said shaft bearing against the platen, a rocker fulcrumed below the gears, means whereby said rocker will be actuated by the cam shafts, and a knife carried by one end of said rocker to cooperate with the fixed knife and 120 sever the paper strip.

7. The combination of printing members, a platen, means for feeding a paper strip over the platen between the same and the printing members, a fixed knife on the 130

- frame adjacent the discharge end of the platen, a train of gears below the platen including cam shafts, cams on said shafts bearing against the platen, a rocker fulcrumed below the gears, means whereby said rocker will be actuated by the cam shafts, vertical ways above one end of the rocker leading to the fixed knife, a knife supported on the said end of the rocker and slideable in 10 said ways to cooperate with the fixed knife and sever the paper strip, and a bowed spring on the rocker and bearing outwardly against the knife.
8. The combination of a frame, printing members mounted thereon, a platen mounted in the frame below the printing members, a counter on the frame, a driving shaft means controlled by the driving shaft for moving the platen vertically to effect im- 15 pressions from the printing members, a cam on the driving shaft, a lever fulcrumed intermediate its ends upon the frame and having one end bearing against said cam, and a link operatively connecting the oppo- 20 site end of said lever with the counter.
9. The combination of a casing, printing members mounted therein, a platen mounted adjacent the printing members for move- 25 ment toward and from the same, means for feeding a paper strip over the platen 30
- between the same and the printing means, means for severing the paper strip, a single rotatable operating handle exterior to the casing for actuating all said means, and a latch on the casing to engage said handle 35 and yieldably hold the same against movement.
10. The combination of a frame, printing members mounted thereon, a platen mounted in the frame below the printing members, 40 rollers mounted in the frame at the ends of the platen, a ribbon carried by said rollers and extending between the platen and the printing members, a counter on the frame, a driving shaft, means controlled by 45 said driving shaft for moving the platen vertically to effect impressions from the printing members, a cam on the driving shaft, a lever fulcrumed intermediate its ends upon the frame and having one end 50 bearing against said cam, a link operatively connecting the opposite end of said lever with the counter, and an arm pivoted to and rising from the said lever and operatively engaging the adjacent ribbon-carrying 55 roller whereby to effect feeding of the inking ribbon.

In testimony whereof I affix my signature.

CHARLES N. WADE. [L.S.]
